UNITED STATES PATENT OFFICE

125,023

DESIGN FOR A CEREAL DISPENSER

Leo E. Kroll, Milwaukee, Wis., assignor of one-half to George Kroll, Milwaukee, Wis.

Application June 21, 1939, Serial No. 85,609

Term of patent 14 years

To all whom it may concern:

Be it known that I, Leo E. Kroll, a citizen of the United States, residing at Milwaukee, county of Milwaukee, in the State of Wisconsin, have invented a new, original, and ornamental Design for a Cereal Dispenser, of which the following is a specification, reference being had to the accompanying drawing, forming a part thereof.

Fig. 1 is a perspective view of a cereal dispenser, showing my new design;

Fig. 2 is a side elevational view thereof; and

Fig. 3 is a top plan view.

I claim:

The ornamental design for a cereal dispenser, as shown.

LEO E. KROLL.
